UNITED STATES PATENT OFFICE.

WALTER JAMES FIELDING, OF BIRMINGHAM, ENGLAND, ASSIGNOR TO SKINNER-HILL CO., OF NEW YORK, N. Y., A CORPORATION OF NEW YORK.

DESIGN FOR A CHANDELIER.

Application filed July 18, 1928, Serial No 27,517, and in Great Britain March 24, 1928. Term of patent 3½ years.

To all whom it may concern:

Be it known that I, WALTER JAMES FIELDING, a subject of the King of Great Britain, and a resident of the city of Birmingham, England, have invented a new, original, and ornamental Design for a Chandelier, as shown in the accompanying drawing.

The figure represents a perspective view of my design.

What I claim and desire to secure by Letters Patent is:

The ornamental design for a chandelier as shown.

WALTER JAMES FIELDING.
